THERMIONIC CATHODE CONSTRUCTION

Ward W. Watrous, Jr., Chatham, N. J., assignor
to Westinghouse Electric Corporation, East
Pittsburgh, Pa., a corporation of Pennsylvania

Application March 9, 1944, Serial No. 525,659

16 Claims. (Cl. 250—27.5)

1

This invention relates to electrical discharge devices, and more particularly to a novel form of cathode heater and heater-containing cathode.

The primary object of my invention, generally considered, is to provide an improved cathode heater and the cathode using the same, avoiding some of the objections of former types of indirectly-heated cathodes.

Another object of my invention is the provision of a cathode heater comprising a refractory insulated core, a helical heater wire portion on the outside and a straight heater wire portion on the inside of said core.

A further object of my invention is the provision of an indirectly-heated cathode with a heater as above described and contained in a hollow cylindrical element thereof defining a heater-receiving space, said heater being held in place with respect to said element by top and bottom cap portions, the former portion with an embossment receiving the top of the core and a depending peripheral flange secured to said cylindrical element, and the latter portion gripping the core in a groove therein and with a dependent peripheral flange also secured to said cylindrical element.

A still further object of my invention is the provision of an extremely simple cathode heater assembly requiring no insulating coating, giving uniform cathode heating, that is, with a minimum temperature gradient from the top to the bottom of the cathode, and because of low mass, heating said cathode faster than previously.

Other objects and advantages of the invention, relating to the particular arrangement and construction of the various parts, will become apparent as the description proceeds.

Referring to the scale drawing:

Fig. 1 is an elevational view, with parts broken away, of a thyratron embodying my invention.

Fig. 2 is an axial sectional view on a larger scale of the cathode of said thyratron, with the heater coil and core shown in elevation.

Fig. 3 is a transverse sectional view on the line III—III of Fig. 2, in the direction of the arrows.

Fig. 4 is an enlarged elevational view of the cathode heating element.

Fig. 5 is a plan of heating element shown in Fig. 4.

Fig. 6 is a diagram illustrating why the cathode

operates at substantially uniform temperature along its axis.

Many different methods have been tried for locating the heater element within and insulated from indirectly heated cathodes in electron-discharge devices. Existing types of indirectly heated cathodes contain as many as three insulators made from very refractory materials, such as alumina and magnesia. Insulators of such materials are difficult to make and expensive, besides greatly increasing thermal mass. Further disadvantages of such constructions are:

(1) Heavy plug at the top of the cathode and insulation of high heat mass.

(2) A molybdenum wire wrapping of the heater leg, which is done by hand.

(3) There is a decided temperature gradient along the axis of the cathode.

In accordance with my invention I provide a cathode heater which:

(I) Has no insulating coating.

(II) Gives uniform cathode heating, that is, a minimum temperature gradient from the top to the bottom of the cathode.

(III) Provides faster heating due to low thermal mass.

(IV) Is extremely simple in construction.

I will now describe a thyratron in which one embodiment of my cathode heater is employed, it being understood, however, that such a heater is adapted for many devices having indirectly-heated cathodes.

Referring to the drawing in detail, there is shown a thyratron 11 comprising a glass or vitreous envelope 12 which is evacuated and provided with a small quantity of filling material, such as mercury vapor or inert gas. The envelope is provided with a re-entrant stem 13 through the press 14 of which extend lead wires 15 making connection with exterior terminal prongs 16 on the bottom of an attached base 16. The opposite end of the envelope is constricted and capped with a terminal member 17, which makes connection with a depending rod 18 sealed 45 through the glass at the upper part of the constricted portion or dome 19 of the envelope and carries a member 21 adapted to form the anode of the device.

Opposed to the anode and suitably supported by lead-in wire 22, and wire 23 the lower end of which is embedded in press 14 is a cathode generally designated 24 and the details of which are shown in Figs. 2 and 3. The cathode 24, in the present embodiment, comprises a generally 55 honeycomb construction, preferably formed of

metal such as nickel, including the central hollow cylindrical portion 25 from which radial fins 26 project to connect with an outer hollow cylindrical portion 27. Such a cathode is desirably constructed of six cells 28, each of which comprises a segment of the cylindrical portion 25, a pair of radial portions 26 connecting with a segment of the cylindrical portion 27, said outer cylindrical segment projecting beyond the radial portion adjacent its free edge so as to allow for connection with the next cell 28, as by means of spot welding or brazing.

The aforescribed construction, as illustrated in Fig. 3, means that the radial members 26 are of double thickness, as compared with the inner and outer cylindrical portions 25 and 27, and conduct heat from the inner cylindrical portion 25, which receives it directly from the enclosed heater member generally designated 29 and shown enlarged in Figs. 4 and 5, thereby providing for efficiently heating all of the walls 25, 26 and 27. The interior surfaces of said walls are desirably coated with electron-emission alkaline-earth material, in accordance with usual practice in making low-temperature electron-emitters.

In order to conserve the heat of the cathode, the honeycomb structure just described is held in an upwardly opening box 31, desirably formed as a hollow metal cylinder closed at the bottom only by an upwardly flanged circular metal portion secured thereto as by welding. The metal used may be nickel or iron. The box 31 is radially spaced from the cathode 24 by inwardly projecting "dimples" or generally spherical embossments 32. This containing box 31 is in turn held in a larger box 33, formed similarly, except as illustrated, and radially and axially spaced therefrom by outwardly projecting "dimples" or generally spherical corrugations 34 in the box 31. The cathode 24 is in turn spaced axially, as desired, from the bottom of the receiving box 31 by connecting straps 49 of nickel or iron, the upper ends of which are secured to the larger box 33 and the lower ends of which are secured to said cathode, as by means of spot welding or brazing.

The outer box 33 is partly closed by an annular flanged member 35, the vertical leg 36 of said member being secured to the upper peripheral portion of the box 33 in any desired manner, as by spot welding, and the lower or horizontal leg 37 projecting inwardly, leaving a constricted opening 38 for the passage of electrons from the cathode. This opening desirably corresponds in size with the opening through associated grids which will be later described. The outer box 33 is directly connected to the lead and support wires, 22 and 23, as by means of spot welding.

The illustrated heater 29, embodying my invention, is received in the central space defined by the hollow cylindrical portion 25 and centered and connected thereto by means of a lower cap member 39, the downwardly projecting peripheral flange 41 of which is secured to the inner cylindrical portion 25 as by means of spot welding, while the upper or annular portion 42 desirably has its inner peripheral portion initially flared, at an angle as indicated at 43, so as to allow for the reception of the heater core 44 of refractory insulating material, such as alumina, beryllia, or magnesia. After assembly said portion 43 may be bent inwardly to grip the restricted portion 45 of said core, as shown most clearly in Fig. 2.

The upper portion of the heater 29 is held in

place with respect to the cathode by an upper cap 46, of nickel or the like, with an upwardly projecting embossment 47 snugly receiving the upper end of said insulator 44 and a depending peripheral flange 48 secured to the upper edge portion of the inner cylindrical part 25 of the cathode 24, as by means of spot welding. The circuit to the heater filament 53 is from a lead 51 extending from the press 14 and connected to the lower end of the straight or internal portion 52 of said filament 53, the other or lower end of the helical portion of said filament being grounded to the cathode structure, as by spot welding to the depending flange 41, so that the current passes between the leads 22 and 51 through said filament 53, cathode structure 24 and enclosing boxes 31 and 33.

The core 44 is not only hollow to receive the straight portion 52 of the heater filament 53, but the upper end portion is provided with a slot 50 through which the portion joining the helical and straight portions of the filament 53 passes, as illustrated in Figs. 2, 4 and 5, so that the extreme upper portion of said filament is below the upper cap 46 and thereby insulated therefrom. At the same time the slot 50 correspondingly lightens the core while leaving it strong enough for the purpose.

Between the cathode 24 and anode 21 is a control grid 54 providing a single circular opening 55 for passage of electrons, said opening being coaxial with the cathode and anode. As shown, the grid includes a generally flat annular plate 56 with depending inner and outer peripheral flanges 57 and 58. The outer peripheral flange 58 is connected to a hollow cylindrical radiator member 59, desirably formed of metal, as by means of welding. The control grid 54 is desirably constructed from material of high heat conductivity and melting point.

The discharge between the cathode and anode is desirably confined by shield grid devices comprising a lower hollow cylindrical section 61 around the cathode and extending almost to the grid plate 56, and an upper hollow cylindrical section 62 extending from just above the grid plate 56 to a position well above the anode 21, said sections being coaxial and of equal diameter. Each shield grid section has a transverse annular baffle therein, the lower section having its baffle 63 between and parallel to the control grid plate 56 and the plane of the upper edge of the cathode 24, while the upper section has its baffle 64 between and parallel to the control grid plate 56 and anode 21. Each baffle has an opening therethrough which desirably corresponds in diameter with that of the control grid plate 56 and the cathode baffle 35, although this is not essential.

The shield grid sections 61 and 62 are carried by supporting wires 65, in turn carried by a collar applied to the stem 13 and clamped securely thereto. These wires project upwardly on the outside of said shield grid sections in contact with the outer surfaces, being welded or otherwise secured thereto. The wires preferably extend to the upper end of the upper section 62, but an upper end portion of each is desirably left unwelded, thereby enabling the same to be bent outwardly and carry beads 66 to brace the assembly with respect to the dome 19 of the envelope 11, in a manner described and claimed in my application, Serial No. 476,158, filed February 17, 1943, now Patent No. 2,353,775, dated July 18, 1944.

The control grid and its radiator are desirably insulatingly supported from the wires 65 and pro-

vided with lead-in conductor 61, the construction of all of said grids and the arrangement and function thereof being more fully described and claimed in my application, Serial No. 503,598, filed September 24, 1943, now Patent No. 2,381,632, dated August 7, 1945.

Referring now to Fig. 6, there are shown graphs to support the statement that the heater gives substantially uniform cathode heating, that is, with a minimum temperature gradient from the top to the bottom of the cathode. It is well known that the maximum temperature of an incandescent filament is between the ends or connections with the lead-in conductors, the presence of lead-in conductors of lower temperature causing the end portions of said filament to assume a considerably lower temperature.

The dash dash graph marked "Temperature of heater filament" represents this condition, the lower end of the filament 53 being the coldest on account of its connection with the cap member 39. Inasmuch as the upper portion or upper end of the coiled portion of the filament is intermediate the ends of the filament, it has a temperature approaching the maximum, whereby the graph of heater filament temperature extends toward higher temperatures as it goes from bottom to near the top.

On account of the cathode structure being open at the top, even though partly closed by the baffle 35, the rate of heat loss therefrom increases from the bottom to the top, as represented by the dotted curve correspondingly marked in Fig. 6. It will, therefore, be seen that the higher temperature of the heater filament at the top, partly at least, compensates for the higher rate of heat loss at the top than at the bottom, thereby giving a general cathode temperature substantially constant as represented by the graph correspondingly marked.

The statement that faster heating is provided due to low thermal mass is clearly shown by considering that the only part of the heater which takes much heat from the heating filament is the single central core member 44 and even this is hollow. This contrasts with the plurality of insulative members formerly employed in connection with heaters of the character disclosed, plus the usual refractory coating of the outside of the heater coil. Of course the member 39 takes some heat from the refractory heating filament but this is desirable in order to provide a substantially uniform general temperature of the cathode, as illustrated in Fig. 6.

From the foregoing disclosure it will be seen that I have devised a novel form of cathode heater and cathode containing the same, and although I have shown it enclosed in a thyratron of special construction, it will be understood that said heater is adapted for use in or with many other cathodes, said heater and cathode are adapted for use in many other electron devices, and the arrangement here shown is merely illustrative.

Although a preferred embodiment of my invention has been disclosed, it will be understood that modifications may be made within the spirit and scope of the appended claims.

I claim:

1. A cathode comprising a hollow element defining a heater-receiving space, and a heater in said space, said heater comprising a refractory insulative core, a top cap for said element with a central embossment receiving the top portion of said core, and a refractory metal heating ele-

ment disposed entirely below said cap and helically wound in engagement with said core.

2. A cathode comprising a hollow element defining a heater-receiving space, a heater in said space, said heater comprising a refractory insulative core and a refractory metal heating element on said core, a bottom cap portion in said space gripping the core at a groove therein and with a depending peripheral flange secured to the lower portion of said cylindrical element, and a top cap with a central embossment receiving the top portion of the core and a depending peripheral flange secured to the upper portion of said cylindrical element.

3. A cathode comprising a hollow element defining a heater-receiving space, and a heater in said space, said heater comprising a refractory insulative core, a top cap for said element with a central embossment receiving the top portion of said core, and a refractory metal heating element engaging said core along its length, said element being a helical portion on the outside and a straight portion running inside of said core, that portion of said element which connects said helical and straight portions lying below said cap.

4. A cathode comprising a hollow element defining a heater-receiving space opening upwardly, and a heater in said space, said heater comprising a refractory insulative core and a refractory metal heating wire on said core, said wire being formed as a helical portion engaging the outer surface of said core, and a straight portion joined to the top end thereof at said core surface and running inside of said core, whereby the greater rate of heat loss from the top of the heater-receiving space is compensated for by the higher temperature of the coil at its top end, giving a substantially uniform operating temperature to the cathode from top to bottom.

5. A cathode comprising a hollow cylindrical element defining a heater-receiving space, a heater in said space, said heater comprising a refractory insulative core and a refractory metal heating element on said core, said element being a helical coil portion on the outside and a straight portion running inside of said core, a bottom cap portion in said space gripping the core at a groove therein and with a depending peripheral flange secured to the lower portion of said cylindrical element, and a top cap with a central embossment receiving the top portion of the core and a depending peripheral flange secured to the upper portion of said cylindrical element.

6. A cathode comprising a hollow cylindrical element defining a heater-receiving space, a heater in said space, said heater comprising a refractory insulative core and a refractory metal heating element on said core, said element being a helical coil portion on the outside and a straight portion running inside of said core, a bottom cap portion in said space gripping the core at a groove therein and with a depending peripheral flange secured to the lower portion of said cylindrical element, a top cap with a central embossment receiving the top portion of the core and a depending peripheral flange secured to the upper portion of said cylindrical element, a plurality of electron-emitting upwardly opening cells surrounding said heater-receiving space, and a baffle partly closing the upper ends of said cells.

7. A heater comprising a refractory insulative core, a refractory metal heating element engagingly encircling said core, and conductive means

engaging said core above and below portions of said heating element for holding said heater in place, one end of said heating element being electrically connected to the corresponding heater-holding means.

8. A heater comprising a refractory insulative core, a filament supported on said core, a portion of said filament being helically wound about, and in engagement with, the exterior of said core, another portion being straight and traversing the interior of said core, said core projecting beyond the junction between said helically-wound and straight filament portions, and means formed with a socket receiving the projecting end portion of said core.

9. A heater, particularly adapted for cathodes of electron devices, comprising a hollow refractory insulative support, a metal cap apertured for receiving said support and with a portion defining said aperture crimped into a restricted portion of said support, and a refractory wire heating element one end of which is connected to said cap and the other end of which passes out of the lower end of said core.

10. A heater, particularly adapted for cathodes of electron devices, comprising a hollow refractory insulative support, a metal cap apertured for receiving said support and with portions defining said aperture crimped into a restricted portion of said support, and a refractory wire heating element a portion of which is wound on the outside of said core with the lower end connected to said cap and the remainder of which extends from the upper end of said wound portion through the interior of said core, so that the other end of said wire passes out of the lower end of said core.

11. A heater comprising a refractory insulative core, a refractory wire heating element, a portion of which is wound on the outside of said core and the remainder of which extends from the upper end of said wound portion through the interior of said core, said core for that purpose being formed hollow and the upper end portion being slotted from the exterior to communicate with said hollow interior, whereby the upper portion of said filament in the connection between the helical and straight portions is disposed below the upper end of said core, and an upper cap embossed to receive the upper end portion of said core without engaging said filament, thereby maintaining electrical insulation between said upper cap and filament.

12. A heater comprising a refractory insulative core, a metal cap apertured to receive said core and with portions defining said apertures crimped into a restricted portion thereof, a refractory wire heating element, a portion of which is wound on the outside of said core with the lower end connected to said cap, and the remainder of which extends from the upper end of said wound portion through the interior of said core, said core for that purpose being formed hollow and the upper end portion being slotted from the exterior to communicate with said hollow interior, whereby the upper portion of said filament in the connection between the helical and straight portions is disposed below the upper end of said core, and an upper cap embossed to receive the upper end portion of said core without engaging said filament, thereby maintaining electrical insulation between said upper cap and filament.

13. An electrical discharge device comprising an evacuated envelope, a cathode therein comprising a hollow cylindrical element defining a heater receiving space, a plurality of electron emitting upwardly opening cells surrounding said space, a baffle partly closing the upper end of said cells, a heater in said space, said heater comprising a refractory insulative core and a refractory metal heating element, said element being a helical coil portion on the outside, and a straight portion running inside of said core, a bottom cap in said space gripping the core at a groove therein, and with a depending peripheral flange secured to the lower portion of said cylindrical element, a top cap with a central embossment receiving the upper portion of said core and a depending peripheral flange secured to the upper portion of said cylindrical element, an electrode adapted to act as an anode and disposed in said envelope opposite side cathode, and grind means disposed between said cathode and anode.

14. A heater particularly adapted for cathodes of electron devices, comprising a hollow refractory insulative support, a metal cap secured thereto to adjacent one end, and a refractory wire heating element, a portion of which engages the outside surface of said core with one end connected to said cap and the remainder of which extends from the other end of said outer portion through the interior of the core.

15. A heater comprising a refractory insulative core, a refractory wire heating element, a portion of which engages the outside surface of said core and the remainder of which extends from one end of said outer portion through the interior of said core, said core for that purpose being formed hollow and one end portion slotted along the length from the exterior to the interior, that part of said filament which unites the inner and outer portions thereof passing through said slotted portion intermediate the core ends.

16. A cathode comprising a hollow element defining a heater-receiving space, and a heater in said space, said heater comprising a refractory insulative generally hollow cylindrical core and a refractory metal heating element, a portion of which is wound on the outer cylindrical surface of said core and lies in engagement therewith, another portion of which runs along the hollow interior of said core, and a third portion of which is disposed intermediate the ends, and passes through a side of, said core, and connects said helical and interior portions.
